Specification for Design.

Patented Apr. 26, 1921.

Application filed January 2, 1920. Serial No. 349,061. Term of patent 14 years.

To all whom it may concern:

Be it known that I, FREDERIK G. WHITTINGTON, a citizen of the United States, and a resident of the city of Chicago, in the county of Cook and the State of Illinois, have invented a new, original, and ornamental Design for an Instrument-Mount for an Automobile Instrument-Board, of which the following is a specification, reference being had to the accompanying drawings, forming a part thereof.

In the drawings:

Figure 1 is a front elevation of a mount embodying this design.

Fig. 2 is an edge elevation of the same.

I claim:

The ornamental design for an instrument mount for an automobile instrument board as shown.

In testimony whereof, I have hereunto set my hand this 26 day of December, 1919.

FREDERIK G. WHITTINGTON.
